UNITED STATES PATENT OFFICE.

MALCOLM HARD, OF FLUSHING, NEW YORK, ASSIGNOR TO THE SUPERHEATER COMPANY, OF NEW YORK, N. Y.

HEATING MEANS FOR INJECTORS.

Application filed May 27, 1926. Serial No. 112,042.

The present invention relates to exhaust steam injectors of the type disclosed in U. S. Patent 1,342,128, granted to James Metcalfe et al., on June 1, 1920, as adapted to be operated, when applied to a locomotive, by a remote control system such as that disclosed in U. S. Patent 1,531,004, granted to M. Hard et al., on March 24, 1925.

In locomotive installations, injectors are exposed to extreme weather conditions and during winter operation the steam and water conduits leading to the injector and the injector itself are subject to freezing. Steam must therefore be provided for periodically heating the injector during periods when it is not in operation and the present invention has for its principal object the provision of simple and effective means for performing this function. A further object of the invention is the provision of means whereby the strainer in the suction line delivering water to the injector may be cleared of any obstruction caused by foreign matter collecting therein, by steam pressure admitted to the injector. Further and more detailed objects of the invention will appear as the following detailed description of a preferred form of the invention proceeds.

In the accompanying drawings, which illustrate the invention, Fig. 1 is a fragmentary view in elevation of an injector installation embodying the present invention. Fig. 2 is a horizontal section on a larger scale taken through the center line of the injector and Fig. 3 is a vertical section taken on the line 3—3 of Fig. 2.

Referring now to Fig. 1, the injector indicated generally at 1 is mounted in the usual position below the locomotive cab and is supplied with water from the tender through the suction line 2 in which is placed a strainer 3. Exhaust steam for operating the injector is supplied through the pipe 4 leading from the engine exhaust passages and the auxiliary and supplemental live steam necessary for the injector operation are admitted respectively through pipes 5 and 6 leading from the main control valve 7 located in the cab of the locomotive and connected by pipe 8 to the live steam turret 9. The injector discharges through the delivery pipe 10 into the locomotive boiler by way of check valve 11.

As shown in Fig. 2, the injector comprises a main housing 12 in which are co-axially

mounted the exhaust steam nozzle or cone 13, water cone 14, a secondary exhaust steam cone 15, the combining tube 16 and the delivery nozzle 17, which delivers the feed water through pipe 10 to the boiler. Exhaust steam is supplied to nozzles 13 and 15 through the exhaust steam supply pipe 4 which opens into the steam chamber 18, the steam supply being controlled by the fluid pressure actuated valve 19. Supplemental live steam at high pressure is delivered by the pipe 6 through the inlet 20 into the supplemental steam passage 21 which communicates with the supplemental steam nozzle 22. Auxiliary live steam is supplied to the injector, when exhaust steam is not available, by the pipe 5 through the inlet 23 opening into the auxiliary steam passage 24, the latter delivering the steam at reduced pressure into the steam chamber 18 through the ports 25. The supply of auxiliary and supplemental live steam is controlled by the main control valve 7, there being no valves located between the latter and the injector. Water is supplied to the injector from the suction pipe 2 through the inlet 26 which communicates with a water chamber 27, in which is located a strainer 28. A port 29 provides communication between the water chamber 27 and a second water chamber 30 leading to the water cone 14, this port being controlled by a valve 31 closing in the direction of normal water flow through the injector and urged to its seat by the spring 32 suitably mounted above the valve and held in the injector housing. The valve 31 is provided with a downwardly extended stem 32 which terminates in a piston 33 mounted in a cylinder formed in the injector housing, this cylinder being in communication by way of passage 34 with the supplemental steam passage 21.

When the injector is idle, valve 31 is seated by spring 32 to shut off the water supply to the injector and when the injector is in operation, valve 31 is lifted from its seat and held in open position by steam entering the cylinder from the supplemental steam passage 21 and acting on piston 33 to raise it and with it the valve. The overflow passage 36 leading from the chamber surrounding the combining tube 16 is controlled by an overflow valve 37 adapted to lift and allow the overflow from the injector to pass

through the passage 38, which terminates in the outlet 39.

It will be obvious from the foregoing that steam admitted to the interior of the injector casing will have free passage through the several nozzles and passages thereof not only to the parts of the injector itself, but will also be free to flow up through the steam pipes 5 and 6 as far as the main control valve and also through the delivery pipe 10 to the check valve 11. Moreover, if sufficient pressure be exerted by steam within the injector, the water valve 31 will be lifted against the water pressure and the pressure of spring 32, and steam will be blown back through the suction line for the purpose of clearing any obstruction in the strainer 28 or the main strainer 3. However, as will be obvious from Fig. 3, steam admitted to the injector for the above purposes will tend, before any appreciable pressure is built up in the injector, to open the overflow valve 37 and escape through the overflow outlet of the injector.

In previous forms of apparatus designed to permit heating of the injector by steam, the overflow valve has been provided with a mechanical connection leading to the cab of the locomotive, whereby the operator could manually keep the valve closed and warm the injector by admitting steam thereto through one of the main steam supply pipes leading to the injector. This method of heating the injector is, however, unsatisfactory as in many cases, due to the location of the injector with reference to the locomotive cab, a complicated arrangement of levers, rods and universal joints is required between the overflow valve and the operating handle in the cab. It is furthermore objectionable to heat the injector by means of live steam admitted through one of the main supply conduits, as in many cases more steam than is necessary is used with a consequent undesirable waste.

In the present invention, the apparatus just referred to is replaced by steam-actuated mechanism which not only supplies heating steam to the injector but which also automatically holds the overflow valve in closed position as long as heating steam is being supplied, and automatically releases it when the heating steam is shut off.

In the preferred embodiment of the invention shown, the delivery chamber of the injector surrounding the nozzle 17 is extended to form a vertical chamber 40 communicating therewith. The chamber 40 is provided with an opening at the top into which is secured the annular guide member 41 in which is mounted plunger 42, the latter passing through the packing gland 43 and terminating in an enlarged end 44 having an opening therethrough which receives one end of the lever 45 pivotally mounted on the injector

housing at 46, and extending beyond the pivot to engage the upper end of the overflow valve stem 47 which projects through the top of the injector housing. The chamber 40 is provided with a threaded opening 70 at the bottom thereof in which is secured, in alignment with the member 41, a member 48 forming a cylinder 49 open at its upper end and connected at its lower end by passage 50 with the steam pipe 51 leading from the tur- 75 ret 9 and controlled by the manually-operated valve 52 located in the engine cab. A piston 53 is loosely mounted in cylinder 49 and is provided with an upwardly extending stem 54 which is adapted to enter the lower end of member 41 and contact with the lower end of plunger 42 when the piston is in its upper position. An automatic drain valve is provided at the bottom of passage 50, the valve being seated by fluid pressure in passage 50 and being raised from its seat by spring 56 in the absence of pressure in the passage. A spring 57 mounted in a recess in the injector housing around the valve stem 47 normally holds the end of lever 45 80 out of contact with the upper end of stem 47.

The operation of the device is as follows. If it is desired to warm the injector during idle periods or thaw it in case it has become frozen, valve 52 is opened and live steam admitted to cylinder 49, forcing piston 53 upwards and with it plunger 42, which, acting through lever 45 and valve stem 47, holds the overflow valve of the injector in closed position.

With the overflow valve thus held closed, steam from the cylinder 49 leaks in appreciable quantity past the piston 53 into the chamber 40 which, as previously noted, is in communication with the delivery chamber of the injector. From this point, if the injector is empty, steam is free to travel through the delivery pipe 10 as far as the boiler check valve and also through the delivery and combining nozzles into the main body of the injector, from which it has free access to both the auxiliary and supplemental steam pipes as far as the main control valve, the latter being located within the cab and consequently in no danger of freezing. If sufficient steam is allowed to accumulate in the injector through leakage past the piston 53, a sufficient pressure may be built up to lift the water valve 31 and allow steam to enter and heat the water passages and suction pipe 2.

Under normal conditions, however, the injector is filled with water during idle periods when heating is necessary, and under these circumstances the heating steam passing the piston 53 will be condensed by the water in the body of the injector and gradually warm the entire apparatus. If left turned on, the continued condensation of the heating steam will cause the injector to

"overfill" and the resultant excess of warm water will lift the water valve and pass into the suction line. Furthermore, as the water in the injector approaches the boiling point, uncondensed steam will pass through the injector and upwardly into the delivery pipe 10, to warm the latter by condensing there.

Because of the fact that a relatively small quantity of steam will leak past the piston 53, the heater valve 52 may be left open for considerable periods of time, as, for example, when the locomotive is idle and exposed to low temperatures, without there being an excessive loss of live steam, as might be the case if it were necessary to open one of the main steam supply pipes for heating purposes.

In case the strainers in the suction line become clogged and it is desired to clear the obstruction, the heater valve is first opened for the purpose of closing the overflow valve as previously described, after which the main control valve may be moved to admit 25 high pressure supplemental steam to the injector. With the overflow valve held closed, a high steam pressure can be built up within the injector forcing steam back through the suction line to clear the latter. While in the 30 form of the injector shown the water valve is automatically lifted by the pressure of the supplemental steam on the operating piston 34, it will be readily apparent that the same action will take place even though the water valve is actuated in a different manner, as the supplemental steam within the injector will create sufficient pressure below the valve 31 to raise it and allow the steam to blow back through the water passages and 35 suction pipe.

As a precautionary measure the piston 53 is formed with a valve face 53^a on its lower side which, when the piston is in its lower position, co-operates with a complementary 45 valve seat formed around the end of the passage 50. The piston in its lower position thus forms a check valve preventing water under high pressure passing from the delivery nozzle of the injector into the conduit 51 when the injector is operating and precluding 50 the possibility of leakage in case the valve 52 or any of the connections in the supply conduit are defective.

It will be apparent that the piston 53 could be made a comparatively tight fit in the cylinder and the heating steam supplied to the injector through a port in the wall of the passage 50 or in the cylinder proper below the piston, but the form of construction 60 shown is to be preferred as it eliminates the undesirable packing of the piston which would otherwise be necessary and, moreover, if such a port were placed in the passage 50 or some equivalent branch passage, 65 the check valve effect of piston 53 in its low-

er position would be lost and the supply conduit 51 would be subjected to the high water pressure existing in the delivery chamber at all times when the injector was in operation.

Many variations and changes in the form and arrangement of the apparatus shown in the preferred embodiment illustrated will suggest themselves to those skilled in the art, but it is to be understood that the embodiment herein shown is for illustrative purposes only and that the invention contemplates all such changes and variations therefrom as may be included within the scope of the appended claims.

I claim:

1. In apparatus of the class described, the combination with an injector having a valve controlled live steam supply conduit and an overflow valve, of a second valve controlled conduit connecting said injector with a source of steam, and fluid pressure actuated means responsive to pressure in said conduit and operating to close said overflow valve upon the admission of steam to said last named conduit.

2. In apparatus of the class described, the combination with an injector having a valve controlled live steam supply conduit and an overflow valve, of a second valve controlled conduit connecting said injector with a source of steam, and fluid pressure actuated means operatively connected to said overflow valve interposed in said conduit, said means being operated to close said overflow valve by steam passing through said last named conduit, whereby said overflow valve is subjected to a closing pressure before steam is admitted to the injector.

3. In apparatus of the class described, the combination with an injector having an overflow valve, of a valve controlled conduit connecting said injector with a source of steam, fluid pressure actuated means for closing said overflow valve extending into said conduit and forming a restriction therein, whereby the flow of steam admitted to the injector through said conduit is limited to a predetermined rate.

4. In apparatus of the class described, the combination with an injector having an overflow valve, of a valve controlled conduit connecting said injector with a source of steam, a cylinder in communication with said conduit and a piston in said cylinder, said piston being operatively connected with said overflow valve to close the latter when steam is admitted to said conduit and cylinder.

5. In apparatus of the class described, the combination with an injector having an overflow valve, of a conduit leading from a source of steam and terminating in a cylinder opening into said injector, a valve controlling the steam supply to said conduit, a piston loosely mounted in said cylinder, and mechanism operatively connecting said pis-

- ton with said overflow valve to close the latter when steam is admitted to the cylinder, whereby opening said control valve operates to close said overflow valve and supplies heating steam to the injector by leakage past said piston.
6. In an apparatus of the class described, the combination with an injector comprising a casing having a ported overflow passage, a 10 delivery nozzle and a chamber in communication with the nozzle, of a valve controlling said overflow passage; a cylinder in communication with said chamber, a piston operatively connected with said valve and loosely mounted in said cylinder, and means for admitting live steam to said cylinder.
7. In an injector, the combination with a check valved delivery line connected to a vessel under high pressure, a plurality of 20 pipes supplying operating steam to said injector, and means adapted to close said pipes, of a water supply pipe, a valve controlling said last named pipe and opening away from the injector, an overflow valve, a valve controlled conduit for supplying heating steam to said injector, and fluid pressure actuated means operated by the admission of steam to said conduit to close said overflow valve, whereby admission of heating steam to said injector creates a pressure therein to open said water valve.
8. In an injector, the combination with a delivery check valved line connected to a vessel under pressure, a plurality of pipes 35 supplying low pressure operating steam to said injector, and means adapted to close said pipes, of a water supply pipe, a valve controlling said last named pipe and opening away from said injector, an overflow valve, a valve controlled conduit for supplying heating steam to the injector, means operated by the admission of steam to said conduit to close said overflow valve, whereby the admission of heating steam to said 45 injector creates a pressure therein to open said water valve, and means to admit high pressure operating steam to said injector when said overflow valve is closed, whereby said water supply pipe may be cleared by 50 high pressure live steam.
9. In an injector, the combination with a conduit delivering a restricted supply of

high pressure live steam and a conduit delivering an unrestricted supply of high pressure live steam to the injector, of an overflow valve closed by the admission of steam to said first named conduit, a water supply pipe, and a water valve therein opened by the admission of steam to said last named conduit, whereby admission of steam to both of said conduits causes steam to flow from the injector through said water valve and said water supply pipe.

10. In an injector, the combination with a plurality of steam supply conduits positively closed against pressure within the injector, of a water supply inlet, a valve controlling said inlet and opening away from the injector, an overflow outlet, a valve controlling said outlet, fluid pressure actuated means for closing said last named valve, and a valve controlled steam supply conduit leading to said means and also in communication with said injector through a restricted opening.

11. In an injector, the combination with a plurality of steam supply conduits positively closed against pressure within the injector, of a water supply inlet, a valve controlling said inlet and opening away from the injector, an overflow outlet, a valve controlling said outlet, fluid pressure actuated means for closing said last named valve, a valve controlled steam supply conduit leading to said means and also in communication with said injector through a restricted opening, fluid pressure actuated means for opening said water valve, and a valve controlled conduit for supplying high pressure operating steam to the injector, said conduit being in communication with said last named means.

12. In an injector, the combination with a plurality of steam supply conduits positively closed against pressure within the injector, of a water supply inlet, a valve controlling said inlet and opening away from the injector, an overflow outlet, a valve controlling said outlet, fluid pressure actuated means for closing said last named valve, and a valve controlled conduit for supplying actuating steam to said means.

MALCOLM HARD.
